TOY CRANE

Edwin C. Olson, New Britain, Conn.

Application February 25, 1946, Serial No. 649,969

8 Claims. (Cl. 294—106)

1

This invention relates to toys, and more particularly to a grab bucket crane for lifting marbles and transporting them in a manner similar to the action of a clam shell dredger.

The present invention provides a realistic imitation of the common industrial operation of loading and unloading trucks, railroad freight cars, etc.

One object of the present invention is to provide a device of the above nature having means whereby the marble may be automatically dumped into a toy truck or freight car.

A further object is to provide a device of the above nature comprising a flat circular casing open at the bottom suspended by a cord from an overhead boom adapted to be carried by the hand of the operator, and in which the casing has located therein a pair of pivoted marble-gripping jaws forming a bucket provided with concave marble embracing bucket elements at their lower ends.

A further object is to provide a device of the above nature in which said bucket has diverging central releasing lugs adapted to engage an in-turned flange on a releasing chamber whereby the marble will automatically be released when lowered upon said chamber.

A further object is to provide a device of the above nature in which the upper ends of the pivoted marble-gripping jaws are provided with outwardly-extending curved lugs for slidably engaging the inner sides of the circular casing, so that said jaws may be permitted to slide easily upwardly therein when lowered upon the marble, and will automatically move to marble-holding position when the casing is lifted.

A further object is to provide a device of the above nature which will be simple in construction, inexpensive to manufacture, easy to install and manipulate, compact, ornamental in appearance, interesting, enjoyable, and instructive to children, and very efficient and durable in use.

With these and other objects in view, there has been illustrated in the accompanying drawing one form in which the invention may be embodied in practice.

In the drawing,

Fig. 1 represents a perspective view of the toy crane as it appears when the marble is being transported thereby.

Fig. 2 is a sectional view taken through the lifting loop at the top of the casing, and showing the bucket when it is being lowered upon a marble prior to the lifting operation.

Fig. 3 is an end view of the same.

Fig. 4 is a sectional view similar to Fig. 2, show-

2

ing the appearance of the buckets after the casing has been lowered upon the marble and the marble-gripping jaws have spread apart and been caused to pass down over the edge of the marble and then moved inwardly and upwardly again to embrace said marble.

Fig. 5 is a view similar to Fig. 4, illustrating the operation of releasing the marble—the releasing lugs of the bucket being engaged by the in-turned flange of the releasing chamber located beneath said buckets.

Fig. 6 is a front view of the pair of opposed jaw members prior to their assembly within the bucket casing.

15 Referring now to the drawing in which like reference numerals denote corresponding parts throughout the several views, the numeral 10 indicates an elongated boom adapted to be carried in the hand of the child or other operator, and 20 having a lifting cord 11 connected to the outer end thereof. The lower end of the cord 11 is connected to a casing 12 comprising a pair of circular sides 13, 14, having in-turned semi-circular abutting flanges 15, 15 and 16, 16—the sides 13, 14 25 of the casing being connected together at the top by a curved arched connecting loop 17. The flanges 15, 16 are provided with spaced bottom ends 18, 18 and 19, 19 having an aperture 20 therebetween.

30 In order to lift a marble so it may be transported from place to place for loading and unloading a toy truck or freight car not shown, provision is made of a pair of T-shaped straight complementary marble-gripping jaws 21, 22, preferably constructed of strip metal. The jaws 21, 22 35 are provided at their intermediate portions with a pair of opposed interfitting slots 23, 24, and have in-turned converging straight upper ends 25, 26 connected to the jaws 21, 22 by a pair of outwardly extending curved lugs 27, 28. The lower ends of the jaws 21, 22 are provided with concave in-turned bucket elements 29, 30, and 40 31, 32, respectively, which embrace a pair of integral diverging central straight bottom lugs 33, 34, as clearly shown in Figs. 2, 3, 4, and 5.

45 The lugs 33, 34 are spaced from the bucket elements 29, 30, 31, 32 by four slots 35, 36, 37, 38, respectively, as clearly shown in the drawing.

In order to permit the marble to be unloaded 50 from the bucket, provision is made of a cylindrical marble unloading chamber 39 (as clearly shown in Fig. 5), which is adapted to be located above the top of a toy truck or freight car (not shown). The unloading chamber 39 is provided with an inclined in-turned wide upper flange 40 having

a central aperture 41, the diameter of which is larger than the diameter of the marble to be carried by the crane, and smaller than the distance between the extremities of the lugs 33, 34 when the marble is in carrying position.

Operation

In the operation of the present invention, when it is desired to pick up a marble from the floor or other surface, the crane boom 10 will be held in the hand of the operator, and the casing 15 will be lowered vertically until the bucket elements 29, 30, 31, 32 engage the marble. The jaws 21, 22 of the bucket will thus be spread apart automatically and will move from the position shown in Fig. 2 to the position shown in Fig. 4, whereupon the marble M may be lifted and transported to any desired location.

When it is desired to unload the marble from the crane, the casing 15 will be lowered over the release chamber 39, causing the lugs 33, 34 at the ends of the bucket to strike the flange 40 of the release chamber. Farther movement of the casing 12 downwardly will cause the marble-gripping jaws 21, 22 to spread apart by a scissors action in opposite directions—the upper ends 25, 26 of said jaws moving upwardly and outwardly from the position shown in Fig. 4 to the position shown in Fig. 5, until the bucket has opened sufficiently to permit the marble to drop through the aperture 41 in the release chamber 39 and be received in the toy truck or freight car.

It will be understood that when the marble is being carried by the bucket, the weight of the marble will pull the bucket elements downwardly and maintain them in tight holding engagement with said marble.

The present invention is also adapted to be used in the playing of the well-known game of "Fishpond" or other games.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a toy crane, a carrying boom, a cord suspended thereby, a casing suspended by said cord and having an open bottom with converging in-turned side walls, a pair of marble gripping jaws centrally pivoted to each other located partly within said casing and having outstanding upper

lugs for slidably engaging the converging side walls of said casing, the lower ends of said jaws being located outside of said casing and having marble-embracing inwardly concave clam-shell bucket-shaped elements adapted to be raised and cammed apart by a marble, and to thereafter close inwardly around said marble by camming of said lugs with said casing side walls to permit said marble to be lifted and transported to another location.

2. The invention as defined in claim 1, in which each jaw is of inverted T-shape.

3. The invention as defined in claim 1, in which said bucket-shaped elements are provided with downwardly-extending outstanding diverging lugs for engaging the inturned flange of a releasing chamber having a central aperture whereby said diverging lugs will spread apart with a scissors action and cause said elements to open to permit the marble to drop into said release chamber.

4. The invention as defined in claim 1, in which said upper lugs have convex outer surfaces.

5. The invention as defined in claim 1, in which said jaws are each of inverted T-shape and have opposed open slots to provide pivot points for said jaws to swing with a scissors action.

6. The invention as defined in claim 1, in which one of said bucket-shaped elements is provided integrally with a downwardly-extending outstanding lug for engagement with a stationary element, whereby said casing may move downwardly with relation to said lug and cause said jaws to open said bucket-shaped elements and permit the marble to drop therefrom.

7. In a toy crane, a pair of gripping jaws centrally pivoted for scissors movement, each of said jaws being formed with an outwardly-extending lug at its upper end, and a cylindrical casing supporting and confining said lugs for cam action against the inner curved surfaces of the casing, said casing having upper means for connection to a suspending cord, and a lower opening whereby gripping portions of said jaws below the lugs will depend from said casing.

8. The invention as defined in claim 7, in which said cylindrical casing is supported with its axis horizontal.

EDWIN C. OLSON.
